UNITED STATES PATENT OFFICE.

BENJAMIN F. WUBBENS, WILLIAM F. HUPP, AND HENRY F. HEGEMAN, OF CEDAR RAPIDS, IOWA.

ELECTRIC WATER-HEATER.

1,322,860.

Specification of Letters Patent. Patented Nov. 25, 1919.

Application filed May 7, 1917. Serial No. 167,022.

To all whom it may concern:

Be it known that we, BENJAMIN F. WUBBENS, WILLIAM F. HUPP, and HENRY F. HEGEMAN, citizens of the United States, residing at Cedar Rapids, in the county of Linn and State of Iowa, have invented certain new and useful Improvements in Electric Water-Heaters, of which the following is a specification.

10 This invention relates to certain new and useful improvements in electric water heaters.

The primary object of the invention is the provision of an easily regulated heater for water which employs electricity as the heating medium, an automatic temperature controller being provided if desired.

15 A further object of the device is the provision of a heater for water especially adapted for household use, the same being easy, and inexpensive to manufacture and arranged for easily regulating the temperature of the water being heated.

20 A still further object of the device is to provide a water boiler having a shiftable electrode means for controlling the temperature of the water, a readily operable flushing device being arranged for the boiler.

25 The figure of the drawing herewith presented is a side elevation of the device operatively positioned with a portion of the boiler and thermostat shown in central vertical longitudinal section.

30 The present drawing illustrates the provision of a boiler 10 filled with water 11 from an inlet service pipe 12 positioned adjacent the bottom thereof while an outlet 13 is arranged for the heated water in the top 14 of the boiler.

35 A binding post 15 is attached to the boiler 10 for electrical connection with a circuit wire 16 while an electrode 17 in the form of a bar is slidably arranged axially of the boiler 10 through a stuffing box 18 of insulating material and centrally positioned in the boiler top 14. A circuit wire 19 is attached adjacent the outer end of the electrode 17 while an operating handle 20 is arranged at the upper end thereof. It will be understood

40 that with the electrode 17 projected to its greatest extent outwardly of the stuffing box 18, only a weak flow of electric current would pass through the water 11 from the conductor 17 to the metallic boiler or tank

45 10 while by forcing the conductor 17 in-

wardly of the boiler to the required extent, the flow of electricity through the water will be increased, producing the required heat for heating the water 11 to the desired temperature. A temperature scale 21 is preferably provided upon the electrode 17 so that the latter by means of the handle 20 may be readily positioned to arrange any desired temperature reading of the scale adjacent the top plate 22 of the stuffing box 60 18 and by allowing the same to remain in such position, the water in the boiler 10 will attain the temperature indicated.

45 A thermostat 23 is arranged for automatically controlling the amount of current supplied to the circuit wires 16 and 19, which latter wires, it will be understood, are in circuit with any desirable source of supply of electricity (not shown). The thermostat 23 consists of a substantially Z-shaped form 70 of tube extending within the water 11 through the side of the boiler 10 and having a vertical rod 23' mounted within the free end of the tube for resting upon the fluid 24, such as mercury which is expanded and contracted by the temperature of the water 11. A terminal 26 is carried by and insulated from the rod 23' and is provided with a circuit wire 25 while a further circuit wire 27 is connected with three contact blocks 28, 75 29 and 30 electrically connected together by suitable resistance 31. It will be understood that when the temperature of the water 11 lowers, the mercury 24 contracting, permits the rod 23' to descend, contacting the terminal 25 with the block 30 for cutting in the highest amount of current to the circuit wires 16 and 19. When the temperature of the water 11 rises, the rod 23' becoming elevated, positions the terminal 25 in contact 80 with either the block 29 or 28 which by means of the resistance 31 correspondingly lowers the amount of electric current furnished to the circuit wires 16 and 19. A set screw 39 may be carried by the thermostat 23 for engagement with the rod 23' for rendering the thermostat inoperative whenever desired.

45 By the manual operation of the electrode 17, the desired amount of current is supplied 105 to the water 11 while the thermostat 23 is designed to be so regulated or synchronized with respect thereto as to control the electric circuit in the wires 16 and 19 that the temperature of the water 11 will be maintained 110

substantially constant at the degree of temperature noted upon the scale 21 at which the electrode 17 is set.

A flushing device 32 is provided for the boiler 10, being in the form of a receiver or can having connection with the lower funnel-shaped bottom 33 of the boiler 10 by means of a connecting pipe 34 provided with a controlling valve 35 therein. An outlet pipe 36 is provided for the can 32 controlled by a suitable valve 37. It will be understood that the can 32 being readily emptied by opening the valve 37, upon closing the said valve and opening the valve 35, the sediment from the tank bottom 33 will be drawn in to the can 32 and on closing the valve 35 and opening the valve 37, any such sediment is readily removed.

Insulating connections 38 are provided in the pipes 12, 13 and 34 while it will be understood that the stuffing box 18 is formed of insulating material so as to insulate the electrode 17 from the tank 10 permitting the operation thereof.

What we claim as new is:—

An electric water heater including an upright elongated boiler having a bottom inlet and a top outlet for the water and provided with a side binding post, and a bar electrode having a binding post at its outer end and vertically slidably into and out of the boiler substantially through the center of the top of the latter, said binding posts being in electrical connection through the electrode and the water, said electrode being insulated from the top of the boiler and being uniformly surrounded at its immersed end by the water, whereby, the deeper the electrode is immersed, the lower down will be the application of heat with a corresponding increase in the rapidity of heating the water.

In testimony whereof we affix our signatures.

BENJAMIN F. WUBBENS.
WILLIAM F. HUPP.
HENRY F. HEGEMAN.
